ATTORNEY

UNITED STATES PATENT OFFICE

JOHN A. LARSON, OF SEATTLE, WASHINGTON

PENCIL SHARPENER AND HOLDER

Application filed July 12, 1930. Serial No. 467,510.

The invention is a pencil clip having a knife blade therein which is arranged so that it may be used for sharpening pencils.

The object of the invention is to provide a pencil sharpener that may be embodied in a clip.

Another object of the invention is to provide a pencil sharpener in which the sharpening blade is open ready for use at all times, 10 and at the same time protected.

A further object of the invention is to provide a pencil sharpener in which a sharpener, clip, and eraser are combined in a single unit.

A still further object of the invention is to 15 provide a combination pencil sharpener and clip which may also be used to protect the point of the pencil.

And a still further object of the invention is to provide a pencil sharpener and clip 20 which is of a simple and economical construction.

With these ends in view the invention embodies a clip having an eraser in one end, and a sharpened blade mounted in an offset 25 portion thereof so that it is adaptable to sharpen pencils.

Other features and advantages of the invention will appear from the following description taken in connection with the drawings, wherein:—

Figure 1 is a view showing the clip in place upon a pencil as it may be used as a clip.

Figure 2 is an enlarged detail showing the face of the clip.

Figure 3 is an enlarged side elevation of the clip with a portion broken away.

Figure 4 is a cross section through the knife blade on line 4—4 of Figure 2.

Figure 5 is a detail showing an alternate 40 means for holding the knife.

In the drawings the device is shown as it would be made wherein numeral 1 indicates a cylindrical section forming the body of the clip, numeral 2 the clip, and numeral 3 the 45 knife.

The body 1 may be of any suitable design or size and is preferably made so that it will frictionally grip the surface of a pencil over which it may be placed. The sides of the 50 member 1 may be provided with slots 4, the

inner edges of which are comparatively sharp so that they will assist in gripping the sides of the pencil. It will be noted that an eraser 5 may be held in the upper end of the body 1.

At the lower end of the member 1 is an extension 6 in which the knife 3 is located, and which also forms the clip 2. The portion 6 extends outward to a point 7, then upward to a point 8, then outward to a point 9; then downward to a point 10, and then outward forming a compound curve which forms the clip 2. The offset portion between the points 7 and 10 is made with the central part removed thereby forming two straps 11 and 12 at the sides with a space between them. The blade 3 may be made of a piece of knife steel with both edges sharpened as shown in Figure 4, and is pressed between the members 11 and 12 so that the edges at the ends will be forced into the sides of the members 11 and 12 in the portions between the points 7 and 8 and 9 and 10, so that when in place the blade 3 will be firmly held. The blade may also be held as shown in Figure 5 by bending a section of metal 13 at the ends of the space between the straps 11 and 12 outward, and then when the knife is in place forcing it against the upper surface of the ends of the knife. The clip 2, which extends downward from the point 10, may be made as shown or may be of any suitable shape or design.

It will be understood that changes may be made in the construction without departing from the spirit of the invention, one of which changes may be in the shape or design of the casing 1, another may be in the use of other means for holding the knife in the clip, another may be in the use of other means for holding the eraser, and still another may be in the use of other means for clipping the device and a pencil held therein to the edge of a pocket or the like.

The construction will be readily understood from the foregoing description. In use the device may be provided as shown, and it will be observed that it may be located at the upper end of a pencil as shown in Figure 1 when the pencil is in use, and it may be removed and placed on the point end of the

pencil to protect the point when the pencil is not in use, as shown by the dotted lines in Figure 1.

When it is desired to sharpen a pencil the device may be removed, and the member 1 gripped in one hand with the pencil in the other so that the blade 3 may be used as a knife to sharpen the pencil. As the blade is sharpened at both edges it may be drawn or forced across the pencil point in any suitable manner. It will also be noted that as the blade is mounted between the straps 11 and 12 it is protected and there is very little possibility of anyone cutting themselves with it either while the device is in use or while it is being used as a clip.

Having thus fully described the invention, what I claim as new and desire to secure by Letters Patent, is:—

- 20 1. In a pencil sharpener and holder of the character described, a cylindrical portion adapted to form a handle and also to fit snugly over a pencil, a comparatively long clip extending from the said cylindrical portion, said clip having an inverted U shaped section therein and said inverted U shaped section having a longitudinal slot therein, and a double edge knife blade positioned in the said slot and held in the ends of the said U shaped section.
- 25 2. In a pencil sharpener and holder of the character described, a tubular member forming a handle and adapted to fit over a pencil, said tubular member having slots in the sides thereof for gripping purpose, a comparatively long clip extending from the said tubular member and having an inverted U shaped section therein, said U shaped section having a longitudinal slot therein, and a double edge knife blade in the said U shaped section and located in the said slot with the edges of the said slot crimped over the edges of the said blade.
- 30 3. In a pencil sharpener and holder of the character described, a tubular member, a clip extending from one end of the said tubular member and having a U shaped portion therein, said U shaped portion having a longitudinal slot therein, and a double edge knife blade in the said U shaped portion positioned in the said slot and held at the ends of the said slot, said blade spaced a short distance from the closed end of the said U shaped portion.
- 35 4. In testimony whereof he affixes his signature.

JOHN A. LARSON.
